UNITED STATES PATENT OFFICE.

DAVID N. LUSE, OF CHINOOK, MONTANA.

NECK-YOKE ATTACHMENT.

SPECIFICATION forming part of Letters Patent No. 703,938, dated July 1, 1902.

Application filed March 29, 1902. Serial No. 100,599. (No model.)

To all whom it may concern:

Be it known that I, DAVID N. LUSE, a citizen of the United States, and a resident of Chinook, in the county of Choteau and State of Montana, have made certain new and useful Improvements in Neck-Yoke Attachments, of which the following is a specification.

My invention is an improvement in neck-yoke attachments for vehicle-tongues, and the invention consists in certain novel constructions and combinations of parts, as will be hereinafter described and claimed.

In the drawings, Figure 1 is a detail perspective view of my invention in the form preferably used on buggy-tongues. Fig. 2 is a detail bottom plan view illustrating the end of the tongue employed in the construction shown in Fig. 1. Fig. 3 is a detail perspective view of the sleeve shown in Fig. 1, showing the pin for operation in the groove of the end thimble of the tongue. Fig. 4 is a perspective view of the construction preferred for use on wagon-tongues. Fig. 5 is a detail side view of the tongue shown in Fig. 4, showing the hole for the connecting-pin. Fig. 6 is a detail perspective view of the central portion of the yoke and the coupling-sleeve of the construction shown in Fig. 4, and Fig. 7 is a detail sectional view.

By my invention I seek to provide in connection with the neck-yoke a sleeve to fit and be secured on the tip end of the vehicle-tongue and provided with a bracing-band at its front end, which band is spaced at its upper side away from the sleeve to receive the devices which connect it with the neck-yoke, the bracing-band being secured to the sleeve and forming the means to which the neck-yoke is connected.

In the construction shown in Figs. 1 and 3 the bracing-band A is secured at its under side and along its sides to the coupling-sleeve B by rivets or brazing, or both, and has its upper side spaced apart from the thimble and elongated laterally and affording a straight square cross-bar A', around which is looped and secured the strap C, which connects with the neck-yoke D. In connecting the strap C with the neck-yoke it may, if desired, be looped around the same or it may be looped around the cross-bar E' of a clasp E, applied to the neck-yoke, as shown in Fig. 1. By

employing the bracing-ring A, as shown, and connecting the strap C directly with the bracing-ring, the coupling-sleeve is relieved in a great measure of the strain and may be made quite light and present in connection with the tip of the pole a neat appearance, as is desired in buggies. In connecting the sleeve with the pole it is preferred to support said sleeve at the extreme tip end of the pole, so there may be no projection of the point of the pole beyond the neck-yoke connection therewith. In connecting the sleeve with the pole the sleeve B is provided with an inwardly-projecting pin or stud F comparatively near its edge and the pole G is provided at its tip or point with the thimble H, shouldered at H' near its rear end and provided in advance of said shoulder with a bayonet-slot H² to be entered by the pin F in adjusting the pole into locking engagement with the sleeve B, which may be effected by slipping the thimble H into the sleeve and then partially turning it, the pin F entering the slot H², as will be readily understood from the drawings. When the parts are so connected, it will be seen there is no projection of the pole beyond the neck-yoke connection, and I thus avoid the difficulty resulting from the catching of the checkreins over the end of the pole and the punching of colts, wagon end-gates, &c., commonly experienced with the ordinary form of neck-yoke connection. At the same time I provide a neat, attractive, safe, and noiseless neck-yoke, as is desired for use on carriages.

In the construction shown in Fig. 4 the pole I is provided on its tip end with the thimble J and with the forwardly-facing shoulder J' and has formed through it in advance of said shoulder the opening J² for the securing-pin. At the under side of the pole in rear of the shoulder J' is secured a ring J³, to which a lead-horse or pair may be coupled whenever desired. The coupling-sleeve K in the construction shown in Fig. 4 is provided with openings K' for the pin K², which is connected by a chain with devices secured to the neck-yoke. This pin K² when passed through the openings K' and J² secures the coupling-sleeve on the pole. The bracing-band L is secured around the sleeve K at the front end thereof and has at its upper side the portions L' and

L^2 spaced away from the sleeve for the connection therewith of the neck-yoke connections M, which are in the form of chains, the bracing-band being secured to the coupling-sleeve at L^3 between the loops L' and L^2 , as shown in the drawings. This construction may be preferred for use on wagons, and it will be noticed that by withdrawing the pin K² the neck-yoke can be readily detached from the pole without removing the neck-yoke from the team.

Having thus described my invention, what I claim as new, and desire to secure by Letters Patent, is—

- 15 1. The combination of the tongue, the thimble fitting on the point of the tongue and having a forwardly-facing shoulder, and a bayonet-slot in advance of said shoulder, the coupling-sleeve provided internally with a pin to enter said slot, the bracing band or ring secured around the front end of said sleeve and provided at its upper side with an extension elongated laterally providing a cross-bar for the connecting-strap, the neck-yoke, and the 25 connecting-strap connected with the neck-yoke and looped around the cross-bar of the bracing-ring substantially as set forth.
2. In a neck-yoke fastening, the combination with the pole, of the thimble upon and at the extremity of the point thereof, the sleeve fitted over and secured to said thimble, the bracing-ring secured upon the said sleeve and provided at its upper side with an extension, and the neck-yoke-connecting devices se-

cured to said extension, substantially as set forth.

3. The combination of the sleeve to fit and be secured upon the end of the pole, the bracing band or strap secured upon and rigidly to said sleeve and spaced at its upper side away from and above the sleeve to afford means for engagement by the neck-yoke connection, the neck-yoke, and the neck-yoke connection secured to the spaced-away portion of the bracing-band substantially as set forth. 45

4. The combination of the pole or tongue provided on its tip end with a thimble and with a forwardly-facing shoulder, the coupling-sleeve fitting on said thimble and against said shoulder, the bracing band or ring secured around the thimble and having at its upper side a spaced-away portion, the neck-yoke, and the neck-yoke connection secured to said spaced-away portion, substantially as set forth. 50

5. In a neck-yoke fastening the combination of the neck-yoke, the coupling-sleeve to fit on the pole, the bracing-band secured for a portion of its length to the band and having a portion extended above and spaced away from the band, and the neck-yoke connection secured to the said spaced-away portion, substantially as set forth. 55
